UNITED STATES PATENT OFFICE.

PAUL FLEMMING COX, OF CHICAGO, ILLINOIS, ASSIGNOR TO THE COX TYPE SETTING MACHINE COMPANY, OF SAME PLACE.

TYPE-SETTING MACHINE.

SPECIFICATION forming part of Letters Patent No. 643,473, dated February 13, 1900.

Application filed April 20, 1898. Renewed July 26, 1899. Serial No. 725,196. (No model.)

To all whom it may concern:

Be it known that I, PAUL FLEMMING COX, of Chicago, in the county of Cook and State of Illinois, have invented certain new and 5 useful Improvements in Type-Setting Machines; and I hereby declare that the following is a full, clear, and exact description thereof, reference being had to the accompanying drawings, which form part of this specification.

This invention is an improvement in type-setting machines; and its object is to provide means for automatically supplying lines of spaces from a large reservoir to the space-channel during the operation of the machine, which reservoir can be filled when necessary without stopping the composition of matter.

The invention is especially designed for use in type-setting machines using compressible 15 spaces, and particularly designed for use with the type-setting machine shown and described in my Letters Patent No. 528,857, of November 6, 1894, and No. 534,550, of February 19, 1895.

25 In my present invention I dispense with the space-making mechanism shown in my latter patent aforesaid, but preferably use crimped spaces, which can be cast in the type-foundry and supplied in page-galleys, the 30 same as the ordinary type are prepared for the market, and practically I propose to have these spaces manufactured in quantities and supplied in galley form, so that such galleys can be readily introduced into the space-reservoir of the machine; and the present invention relates particularly to the means whereby the lines of spaces may be successfully 35 separated from the galley in the reservoir and moved into the space-holding channel of the 40 machine and then fed as desired by the operator; and a further object is to render the operation of separating the lines of spaces and their transfer to the space-channel of the 45 machine automatic.

50 While I show and describe the invention as used to supply crimped spaces to the space-channel of the machine, it is obvious that flat or other forms of spaces could be operated upon or that the invention might be utilized 55 to feed character-types, quads, &c., to the proper channels, and therefore while refer-

ring to "spaces" for simplicity of explanation I do not confine myself to such a limited use of the invention.

My invention therefore consists in the mechanical combinations and constructions of parts summarized in the claims and will be fully understood from the following description in connection with the drawings forming part of this specification, to which reference is had by letters of reference marked thereon.

In said drawings, Figure 1 is an end or side elevation of the space supplying and feeding mechanism as applied to my patented type-setting machine aforesaid. Fig. 2 is a front elevation of Fig. 1. Fig. 3 is a top plan view, partly in section. Fig. 4 is a vertical section on line 4 4, Fig. 2, looking to the left. Fig. 5 is a transverse section on line 5 5, Fig. 2, 70 looking down. Figs. 6, 7, 8, and 9 are details.

A designates the space-reservoir, which is set vertically edgewise at a convenient point on the machine above the carrier-belt or type-assembling point. This reservoir is adapted to receive a galley of ready-made spaces or type S just as they come from the type-foundry, the outer side A² of the reservoir being hinged or removable, so that a galley of 75 spaces can be easily inserted therein, and then side A² can be closed and fastened by catches A³ or in other convenient manner. Within this reservoir is a vertically-arranged horizontally-movable plunger B, having a lateral 80 arm b extending into a guide a on the rear edge of reservoir A and connected to a cord B', which runs over a series of pulleys b² b³ and is attached to a weight (not shown) on its lower end, by which the plunger is moved forward in the reservoir and continually presses the spaces therein toward and against the front plate a', which closes the front edge of the reservoir, as shown.

C represents a vertically-disposed horizontally-movable plunger located at the front end of the reservoir and movable at right angles to plunger B and adapted to work just behind plate a' and to move the foremost vertical line of spaces s horizontally out of the 95 reservoir through a slot a² (at the front end and in the inner side thereof) into a vertical

space-channel D beside the reservoir. The plunger C has a horizontal arm C', which extends across the plate a' and is supported in a guide a³, attached to said plate. The arm C' is slotted at C² for the reception of the end of a vibrating arm c on a vertical rock-shaft c', which is journaled in suitable supports, and on its lower end is an arm c², carrying a friction-roller c⁵, which engages a cam-groove in the face of a horizontally-disposed cam c³, fixed on a vertical stub-shaft c⁴, (which is operated as hereinafter described,) and at each rotation of cam c³ the plunger C is reciprocated once. Working within the channel D is a vertically-movable plunger or presser D', which descends by gravity and presses upon the line of spaces in channel D. This presser is raised by means of a link d, connected to the longer arm of a bell-crank lever d', which is pivoted on a support near the rear end of the extension a of the reservoir, and the short arm of the lever d' is connected by a link d² to the long arm of a bell-crank lever d³, the short arm of which carries a roller d⁴, which is adapted to contact with a cam d⁵ on the upper end of shaft c⁴. By this arrangement of levers and cams the presser D' can be lifted clear above the slot a² of the reservoir before the plunger C is operated, and the cams d⁵ and c³ are so fixed upon the shaft c⁴ that the presser D' and plunger C are operated successively at the proper time.

The shaft c⁴ is automatically rotated once at the proper time by means of the following devices: Loosely mounted upon shaft c⁴ below cam c³ is a gear E, which meshes with a pinion e on a vertical shaft E', which is driven by bevel-gears e' z from the main shaft Z of the machine. The gear E is just below cam c³, and on the lower face of this cam is pivoted a dog F, provided with a biting-tooth f and a cam-tooth f', which latter is pressed outwardly by a spring F', also attached to the under side of the cam c³. (See Fig. —.) On the upper surface of gear E is a single-tooth ratchet or lug E², which rotates continuously with the said gear and is adapted to engage the tooth f of dog F and rotate the cam c³ and shaft c⁴, to which the cam is keyed, whenever spring F' is permitted to shift the dog F so as to throw its tooth f inward. The dog F is normally kept out of engagement with lug E² by means of a trip G, which is pivoted on a stationary support T just below and beside the cam c³ and has a finger g, which normally projects inward between cam c³ and gear E in position to engage the cam-arm f' of pawl F, so as to cause its tooth f to disengage and keep clear of the lug E², and consequently prevents the rotation of shaft c⁴ from the gear. The trip G is locked in such position by means of a catch H, which is pivoted on a support T at right angles to the trip and engages an arm g' of the latter, the catch being held in engagement with the trip by means of a spring H'. The catch is caused to automatically release the trip, as

the presser D' reaches the lowest point of its movement, by means of the trip-rod h, which is connected to the vertically-movable lever d' and hangs directly over the trip, through a guide h'. As soon as this trip-rod disengages the catch from the trip G spring F' pushes arm f' of the dog outward, throwing its tooth f into position to engage the lug E², whereupon the shaft c⁴ is rotated and the presser D' and plunger C operated as described. Of course the trip-rod h is lifted with the presser D' and allows the catch H to lock trip G, which is thrown back, as hereinafter described, in position to cause its arm g to engage cam f' of pawl F and disengage the tooth f of the latter from the lug E². Consequently shaft c⁴ only makes one revolution for each descent of the presser D'. The trip G has a third arm g², provided with a pin g³, that is adapted to press against the edge of cam c³, the periphery of which cam is notched at c⁶, so as to permit a slight oscillation of the trip when catch H is disengaged therefrom; but as the pin g³ rides up out of the notch the trip G is returned to normal position and locked by catch H, as described.

The spaces are ejected from the lower end of channel D into a guide-channel I, by which they are directed onto the carrier-belt or directly to the assembling-point, as indicated. As shown, the spaces are ejected laterally from channel D by a reciprocating plunger J, the upper surface of which (when corrugated spaces are employed) will conform to the shape of the spaces. This plunger is operated by a bell-crank lever J', the upper arm of which engages the ejector, and its lower arm carries a roller j, which rests upon the periphery of a cam-disk K, which is loosely mounted on a short horizontal shaft L, driven by beveled gears L' and E² from shaft E', as shown. The cam K is clamped between friction-disks l, keyed on shaft L, so that said cam will rotate with shaft L unless the cam is locked. The cam K is, in fact, locked at every revolution by means of a pin k on the cam, which engages one end of a pivoted trip M, the other end of which is engaged by a catch N, that is connected by a rod N' to the space key or lever, (not shown,) but substantially as described in my Patent No. 534,550 aforesaid. The trip M is held in position to engage the pin k by a spring M', which spring, however, will not prevent the rotation of the cam K if the catch N is disengaged from the trip M.

The operation of the device may be briefly summarized as follows: The plunger B is drawn back to its extreme rear position and a galley of spaces is placed in reservoir A, the columns of spaces being vertical, as shown, and the plunger C being also retracted out of the way. The plunger B then presses the whole body of spaces forward against the plate a', and plunger C is then operated so as to move a line of spaces through a slot a²

into the channel D, the presser D' being previously lifted. From the channel D the spaces are fed as needed to the composing mechanism by depressing the rod N'. As the spaces 5 are removed from the channel D, presser D' descends, and when its lower end reaches the level of the bottom of the reservoir the trip-rod h causes catch H to release the trip G, and immediately the spring F' causes pawl F to be engaged by the lug E² on the continuously-rotating gear E, and the cam c³ and shaft c⁴ and cam d⁵ are rotated once, as described. During their rotation the cam d⁵, through the 10 described levers, first raises presser D' above slot a². Then the cam c³, through the described connections, reciprocates plunger C, which moves a vertical line of spaces edge-wise through the slot a² into the channel E. Meanwhile the cam c⁶ has returned trip G 15 into position to cause pawl F to disengage the ratchet, and consequently the cams c³ and d⁵ are stopped after making one complete revolution and remain stopped until the presser D' again descends sufficiently to cause rod h 20 to disengage catch H from the trip G. These operations take place automatically. When the last line of spaces has been removed from the reservoir into channel D, an attendant can put another galley of spaces therein, there 25 being enough spaces left in the channel to last during the charging of the reservoir, so that there need be no waiting or loss of time by the operator.

By depressing the space-key, rod N' is depressed, disengaging catch N from trip M, and thereupon the cam K rotates once and operates the ejector J, the cam being arrested, however, after making one rotation, by the trip M unless the space-key be held down or 30 again depressed.

I have especially designed this mechanism for handling crimped spaces such as I describe in my Patent No. 528,857, of November 6, 1894; but it is equally applicable to handling other kinds of spaces and type.

As various changes may be made in the positions, constructions, and arrangements of the parts and the relative locations thereof in relation to the other portions of the machine within the scope of my present invention, I do not limit myself to the specific construction and arrangement of parts shown and described.

Having thus described my invention, what 55 I therefore claim as new, and desire to secure by Letters Patent thereon, is—

1. In a type-setting machine, the combination of the space-channel, a space-reservoir, and a plunger adapted to transfer lines of 60 spaces from said reservoir to said channel, and a rock-shaft and levers for operating said plunger; with a shaft carrying a cam for operating said rock-shaft, a continuously-rotating gear on said shaft beside said cam, a pawl 65 carried by said cam adapted to engage a lug on the gear, and a trip adapted to cause said pawl to disengage said lug, and means for

causing said trip to release the pawl, substantially as and for the purpose described.

2. In a type-setting machine, the combination of the space-channel, the presser therein and levers for lifting said presser; a space-reservoir and a plunger adapted to transfer lines of spaces from said reservoir to said channel, and a rock-shaft and arms for operating said plunger; with a shaft carrying a cam for operating said levers and a cam for operating said rock-shaft, a continuously-rotating gear on said shaft beside one of the cams, a pawl carried by such cam adapted to engage a lug on the gear, a pivoted trip, adapted to cause said pawl to disengage said lug, a catch for said trip, and means for disengaging said catch, controlled by the descent of said presser, substantially as and for the purpose described.

3. In a type-setting machine, the combination of the space-holding channel, the space-ejector therein, a continuously-rotating shaft, a cam frictionally mounted thereon, and a rock-lever for operating said ejector adapted to be actuated by said cam; with the pivoted trip for locking said cam, the catch for locking the trip, and means substantially as described for releasing the catch when the space key or bar is depressed, substantially as and for the purpose described.

4. The combination of a rotatable shaft, a cam fixed thereon, a gear loosely mounted on said shaft, and means for continuously rotating said gear, a device on said cam adapted to engage said gear and lock the cam thereto, and a trip for disengaging the pawl from the lug, and means for controlling the trip, substantially as described.

5. The combination of a rotatable shaft, a cam fixed thereon, and a gear loosely mounted on said shaft, beside the cam, and means for continuously rotating said gear, a device on said cam adapted to engage said gear and lock the cam thereto, a pivoted trip for disengaging the device from the gear, whereby when said trip is released, the cam is locked to the gear, and a pin on the trip adapted to engage a cam-notch in the periphery of the cam; 115 whereby the trip is thrown into position to cause the device to release the gear when the cam has made a complete revolution, substantially as described.

6. In a type-setting machine, the combination of a space-channel, a space-ejector, a rocking spring-retracted lever for operating said ejector, a continuously-rotated shaft, a cam for operating said lever loosely mounted on said shaft, friction-clutches for causing 125 said cam to rotate with the shaft, an oscillating trip for locking said cam, and a catch for locking said trip, and a rod for disengaging said catch connected to the space-bar, all substantially as described.

7. In a type-setting machine, the combination of the space-channel, the presser therein, the space-reservoir beside the channel communicating therewith, a plunger for moving

the line of spaces from the reservoir into the channel, and a rocking shaft and levers for operating said plunger from a race-cam, with a stub-shaft carrying said cam, a loose gear 5 on said shaft, means for continually driving said gear, a pawl carried by said cam adapted to engage a lug on said gear and lock the cam thereto, a trip for disengaging the pawl from said gear, and the catch for locking said trip 10 and means for causing the catch to release said trip, when the presser descends to a certain point, substantially as described.

8. In a type-setting machine, the combination of the vertically-disposed space-channel, 15 the presser therein, the levers for raising said presser, the space-reservoir beside the channel communicating therewith, a plunger for moving the line of spaces from the reservoir into the channel, a rock-shaft and levers for 20 operating said plunger, and means for forwarding the spaces in the reservoir; with a

vertically-disposed stub-shaft, a loose gear thereon, means for continually driving said gear, a cam on said shaft for operating said presser-levers, a race-cam on said shaft for 25 operating said rock-shaft, a pawl carried by said race-cam adapted to engage a stop on the said gear and lock the race-cam thereto, a trip for disengaging the pawl from said gear, and a catch for locking said trip, and a trip-rod 30 connected to said levers adapted to disengage the catch from said trip when the presser descends to a certain point, substantially as described.

In testimony that I claim the foregoing as 35 my own I affix my signature in presence of two witnesses.

PAUL FLEMMING COX.

In presence of—

ORVILLE D. ORTON,
JAS. A. WOOD.
